UNITED STATES PATENT OFFICE.

WENDELL L. SHEPARD, OF TRENTON, NEW JERSEY, ASSIGNEE, BY DIRECT AND MESNE ASSIGNMENTS, TO KEYSTONE CAP COMPANY, OF WILMINGTON, DELAWARE, A CORPORATION OF DELAWARE.

CAP-MAKING MACHINE.

1,202,596.

Specification of Letters Patent.

Patented Oct. 24, 1916.

Application filed November 2, 1914. Serial No. 869,911.

To all whom it may concern:

Be it known that I, WENDELL L. SHEPARD, a citizen of the United States, and a resident of Trenton, Mercer county, State of New Jersey, have invented certain Improvements in Cap-Making Machines, of which the following is a specification.

One object of my invention is to provide a relatively simple, compact and efficient machine for making milk bottle caps or similar punched pieces, the various parts being so arranged that a web of paper is first printed in one or more colors with the directions or advertising matter which it is desired shall appear on the finished caps, after which the printed parts of the paper web are cut out and then returned to the holes in the web, which carries them from the machine proper to reciprocating strip-pers designed to force them out of the holes in which they have been held by friction. The caps are then collected upon a suitable conveyer which delivers them to a paraffin applying apparatus, or to any desired receptacle.

Another object of the invention is to provide novel means for removing from a punching machine, milk bottle caps or other pieces after they have been punched or cut from a web of sheet material.

These objects and other advantageous ends I secure as hereinafter set forth, reference being had to the accompanying drawings, in which:—

Figures 1 and 2 are elevations of the opposite sides of the preferred form of machine constructed according to my invention; Figs. 3 and 4 are elevations of the opposite ends of the machine; Fig. 5 is an elevation, partly in section, taken on the line *a—a*, Fig. 1; Figs. 6 and 7 are enlarged transverse vertical sections taken on the lines *b—b* and *c—c*, Figs. 5 and 4, respectively, illustrating the detail construction of the printing and punching mechanism of my machine; Fig. 8 is a plan of a portion of the paper web after a series of caps have been cut therefrom; Fig. 9 is a plan of a bottle cap printed and cut out by my machine, and Fig. 10 is a plan of part of my machine.

In the above drawings, 1 represents a supporting base frame carried on legs 2 and serving to support three relatively heavy open rectangular frames 3, 4 and 5 of which the first two are designed to carry the printing mechanism and the last is for the purpose of supporting the punching or cutting out apparatus. Each of these frames has a suitably projecting bracket 6 providing bearings for a driving shaft 7, on which is rotatably mounted a driving pulley 8. Fixed to the shaft is a fly wheel 9, with three beveled pinions 10, 11 and 12, there being provided a clutch 13 whereby the driving pulley 8 may be operatively connected to or disconnected from said shaft 7 at will. For operating this clutch, I connect an arm 14 to its movable member and attach the outer end of said arm to a rod 15 slidably mounted in arms 16 projecting from two of the bearing brackets 6. This rod has fixed to it a pair of handles 17 whereby it may be operated from either end of the machine. The two frames 3 and 4 with the printing mechanism carried thereby are substantial duplicates of each other for the purpose of two-color printing, and obviously either of them may be omitted or a greater number than two may be employed without departing from my invention.

In the case of the frame 3, for example, a shaft 18 extends through suitable bearings in its upper part, having fixed to one end a beveled gear 19 meshing with the pinion 10 on the driving shaft 7, and carrying a pair of cranks 20, on each of which is journaled a connecting rod 21 of the construction shown in Fig. 6. For purposes of adjustment, said rod is made in three sections 22, 23 and 24 rigidly connected together, and in the present instance there is a threaded member 25 connecting the sections 22 and 23 with a second threaded member 26 connecting the sections 23 and 24.

Hinged to the member 24 of the connecting rod is a casting 27 forming a head on which are adjustably carried a series of blocks 28, each having fixed to it an electrotype plate or other structure 29 forming a printing member. Each of these blocks

is held to the head 27 by two bolts 30 and 31, extending at right angles to each other, the first passing through a vertical slot in the head so as to be movable with its block 5 toward and from the front of the machine, while the second bolt is carried by a plate 32 extending downwardly from one edge of the head 27. The electrotype is held to the block 28 by clamps or any other suitable 10 means, and the press bed with which said type co-operates is formed by the transverse bottom member of the frame 3, on which is mounted a pad 33 of any suitable material, such as cardboard.

15 For supplying ink to the type I provide a fountain consisting of a container 34 mounted on one face of the frame 3 and having its bottom formed by a suitable roller 35 coacting with two other rollers 36 and 37, 20 each of which extends transversely across the machine. A distributing roller 38 for transferring ink from the roller 37 to the face of the electrotype 29, is carried on arms 39, respectively hinged to downwardly extending arms 40 on a shaft 41 and connected to them by springs 42, there being a stop 43 for determining the relative positions of said arms under the action of the springs.

The shaft 41 is carried in bearings at opposite sides of the frame 3, and has fixed on one end an arm 44 provided with a pin 45 operative in a cam groove 46, formed in a disk 50 (Fig. 1) carried by the shaft 18; the arrangement of parts being such that 35 while the head 27 is raised, the arms 40 and 39 are so turned as to cause the roller 38 to pass over the face of the electrotype 29 into engagement with the roller 37 and thence back over the electrotype to the position 40 shown in Fig. 6.

At either side of the frame 3 immediately under the roller 38, I form a U-shaped structure 47 of a thin bar or heavy wire extending from front to back in such positions as 45 to receive and support the roller 38 in case the springs 42 should break in order to prevent it from so far falling as to be damaged by catching on the bed portion of the frame 3.

50 A second laterally elongated bar or wire structure 48 is also provided preferably immediately in front of the bed portion of the frame, in position to receive and hold down the paper web α just before it passes over 55 the bed. Both of these frames or supporting structures 47 and 48 are preferably held in place by the nuts of the bolts 49, which primarily hold the frame 3 to the base structure 1 of the machine.

60 Any suitable gearing may be employed for actuating the inking rollers, though in this instance I have shown each of the cam disks 50 as having grooves for the reception of a driving belt 51 extending around a second

65 pulley 52 fixed to the spindle of the inking roller 37. This spindle has an eccentric portion 53 designed to reciprocate a pawl placed to co-act with the teeth of a ratchet wheel 55 on the spindle of the fountain roller 35, so that this shaft is periodically rotated 70 through a predetermined arc, and in turn actuates the rollers 36 and 37 in the well known manner. Since the inking apparatus carried by the frame 4 is in every way identical with that carried by the frame 3, I 75 have applied to it the same reference letters as have been used in describing said mechanism.

For feeding the paper web α through the machine, I provide a pair of nip rolls 56 and 57, whose spindles are supported in bearings carried by brackets 58 at the front end of the base structure 1. The spindle of the roller 57 has fixed to it a gear wheel 59 meshing with a second gear wheel 60 carried 80 by the spindle of the roller 56, which also has fixed to it a ratchet wheel 61 acted on by a pawl 62 carried by an arm 63 pivoted on said roller spindle. This arm through a link 64, is connected to the cam disk 50 so 85 that as the latter rotates said arm is oscillated and causes the pawl 62 to periodically turn the ratchet wheel 61, with the rollers 56 and 57, through a predetermined angle.

For cutting out the caps from the paper 95 sheet α , I provide on the frame a suitable 100 punch mechanism consisting primarily of a transverse shaft 65 journaled in the top portion of said frame and driven from the pinion 12 on the main shaft 7 through a beveled gear wheel 66. As shown in Fig. 4, this shaft has two cranks 67, on each of which is mounted a connecting rod 68, and both of said rods are pivoted or hinged to a head 69 slidably guided in ways at the side of the 105 frame 5. Two lines of punches 70 (Fig. 7) are supported by this head so that those of one line are staggered relatively to those of the other, and both sets are removably mounted in a block 71 held to the under side 110 of the head 69 by bolts 72 passing through slots therein in such manner that it may be adjusted across the head, by proper manipulation of screws 73 passing through arms 74 attached to the latter. Each of the 115 punches consists of a hollow cylinder having a sharpened lower edge and provided with an ejecting plunger 75 normally maintained adjacent said edge by means of a spring 76.

120 The lower member of the frame 5 carries a transversely extending block 77 on which are detachably supported a series of disks 78, so placed as to co-act with the punches 70.

Supported on arms 79 projecting rearwardly from the punch head 69 are two series of stripper plungers 80 and 81, whose center lines are so spaced apart as to corre-

spond with the spacing of the center lines of the punches 70 and therefore of the set of holes formed by one operation thereof, it being noted that the stripper plungers 81 are 5 slightly longer than the plungers 80.

Fixed to the shaft 65 is a grooved wheel or pulley 82 connected by a belt 83 to a pulley 84 on a shaft 85 journaled in bearings adjustably carried by brackets 86. This 10 shaft carries a roller 87, around which passes a conveyer belt 88 extending also under a plate or table 89 having openings in the line of movement of the plungers 80 and 81 and so placed that the paper web α passes over it. 15 After its passage over said table this paper web is guided around a roller 90 and thence to a winding roll.

Under conditions of operation, the shaft 7 is driven by power applied to the belt 20 wheel 8, and in turn causes rotation of the two shafts 20 and the shaft 65. Through the belts 51, the inking rollers are also rotated and the cam grooves 46 of the cams 50 acting on the pins 45 of the arms 44 periodically cause the ink distributing rollers 38 to collect ink from the rollers 37 and deliver it to the printing faces of the electrotypers 29; it being understood that while 25 in the present case two sets of these latter 30 are applied to the blocks 28 and while different colored inks are supplied to the two fountains 34, any desired number of sets 35 may be employed without departing from my invention.

The paper or pasteboard web from which the caps are to be made is of a width determined by the number of punches, and is directed between the nip rolls 56 and 57 by 40 guide plates 92 fixed to a cross bar 93 adjacent the opposite ends of the same, so that it is delivered through said rolls in a predetermined position relatively to the other parts of the machine. These nip rolls are periodically actuated through the link 64, 45 arm 63, pawl 62 and ratchet wheel 61, and therefore at each operation of the machine feed the web α forward a distance which in the present case is equal to some multiple of the distance between the centers of the 50 frames 3 and 4 or 4 and 5.

Owing to the revolution of the shafts 20, the heads 27 carrying the electrotypers or type, etc., are reciprocated in the guideways of their respective frames 4, and the various 55 parts are so assembled that such reciprocation takes place while the paper web α is held from moving by the nip rolls 56 and 57. The operation of the printing mechanism carried by the frame 3 in the particular apparatus illustrated, prints certain ornamental figures, advertising matter or instructions in an ink of one color upon the paper web, forming lines of impressions staggered 60 relatively to each other, although it is obvi-

ous that if desired, the type may be omitted 65 from any particular portion of the block 28, so that blank spaces will be left which are later filled in with printed material in the differently colored ink applied by the printing mechanism carried on the frame 4. It is 70 also to be noted that more or less of the electrotypers of either or both rows may be different, if desired.

At the next operation of the feed or nip rolls 56 and 57, the paper web α is moved 75 forward for the predetermined distance, and finally that portion of said web which was previously printed is brought into proper position under the type carried by the frame 4, it being obvious that the type carrying 80 block 28 of this second frame may be adjusted so that when the head 27 is reciprocated, the impressions will be made on the web in proper register relatively to the impressions previously made in ink of another 85 color.

Succeeding operations of the feed rolls 56 and 57 bring the printed portions of the paper web under the punch head 69, which upon being reciprocated, causes the punches 90 70 to cut out the two lines of printed disks from said web and after receiving said disks within their bodies during the completion of the down stroke of the punch head, return them under the action of the spring 95 100 pressed plungers 75, to the holes from which they have been cut, flush with the surface of the web. The parts of the machine are so proportioned and adjusted that the disks of material cut out have the printed material previously applied to the web properly centered upon them, and upon the next movement of said web or after a certain number of said movements, that portion 105 thereof carrying the cut out pieces of material is brought directly under the stripping plungers 80 and 81, which being carried by arms 79 attached to the punch 69, are reciprocated therewith. Upon the next 110 succeeding downward movement of the punch head, the plungers 81 are first caused to engage the disks of one line, while those of the other line are immediately thereafter engaged by the plungers 80, so that both sets of disks are forced out of the holes in 115 the paper web in which they have previously been carried, and are dropped on to the traveling apron or conveyer 88, while the punched paper web passes around guide roll 90 to a suitable receptacle or winding roll. 120

Obviously if all of the caps or pieces formed by the punches are all alike as to size and printed matter upon them, a single receptacle placed at the discharge end of the conveyer 88 would be used to collect 125 them. One feature of my invention, however, resides in the provision of means whereby differently printed caps may be sorted

or separated and for this purpose I provide separate receptacles for receiving the caps formed by the respective punches or by a plurality of sets of adjacent punches and printing apparatus.

In the case illustrated, the machine is so adjusted that the caps formed and printed by each pair of adjacent punches and their coöperating type are alike, and in order 10 that the caps in each pair of adjacent lines may be directed to a single receptacle I provide laterally adjustable deflectors as shown in Fig. 10. These consist of flat and preferably pointed pieces 100 of suitable material mounted on a crossbar 101 extending over the conveying apron 88, preferably adjacent its discharging end and so arranged that the caps in two adjacent lines, indicated at $y-y$, are so shifted on the conveyer 15 as to be delivered into a single receptacle 102. The caps from two other lines indicated at $y'-y'$ are likewise so moved upon the apron as to be delivered into another receptacle 103, etc.

20 Obviously suitable numbers of the deflectors 100 may be removed so that the caps in any desired number of lines may be delivered all into a single receptacle which would necessarily be of suitable dimensions 25 to receive them. Of course, if the caps delivered by the machine were spaced sufficiently far apart upon the apron 88 the deflectors 100 would not be required since said caps would be delivered into properly placed 30 receptacles 102-103 without necessitating alteration of their positions.

By forming one set of stripping punches of such length as to engage one set of the frictionally held disks in the web before the 40 other is engaged, the work required of the machine in stripping is performed at two different times rather than all at one time, while by returning the cut out disks to the web and thereafter moving them with it 45 away from the punches, I effectually prevent any clogging or other interference with the action of the apparatus. The crossmember of the bar 48 adjacent the punch head 69 serves as a stripper to prevent the rise 50 of the paper web with the punches, while the bars 47 effectually guide the web as it passes through the machine.

I claim:—

1. The combination in a cap punching machine of a web feeding device; a punch head; means for reciprocating said head; a series of punches carried by the head; means for returning to the web the disks cut out by the punches; and strippers carried by the 60 head in position to directly engage and remove the disks held by the web after the latter has carried them away from the punches.

2. The combination in a cap punching machine of a web feeding device; a hollow re-

ciprocable punch; a yieldingly supported 65 plunger carried thereby in position to return to the web the disks cut out of the same by the punch so that they are frictionally held; and means for removing certain of the disks from the web at one time and other 70 disks at another time.

3. The combination in a cap punching machine of means for feeding a web of material; mechanism for punching a plurality of lines of disks from the web and thereafter 75 returning them thereto; with a plurality of sets of successively acting strippers mounted to remove the disks from the web after the latter has carried the same away from the punches. 80

4. The combination in a punching machine of a web-feeding device; punching mechanism including a plurality of lines of punches for cutting out a plurality of lines of disks from the web and then returning 85 them thereto; with a plurality of sets of strippers mounted to remove the disks from the web after they have been carried thereby away from the punches, certain of said strippers being mounted to act on the disks 90 before others.

5. The combination in a cap punching machine of web-feeding means; a frame; a punch head reciprocable therein; a plurality of sets of strippers carried by the punch 95 head; mechanism for actuating the punch head; a plurality of sets of punches also carried by said head; and means carried by the punches for returning to the web the disks cut out of the same by the punches, 100 the strippers of one set being mounted to engage the disks of one set of the same before the strippers of the other set come into operation.

6. The combination in a cap punching machine of web-feeding means; a frame; a punch head reciprocable therein; a plurality of sets of strippers carried by the punch head; mechanism for actuating the punch head; a plurality of sets of punches also 110 carried by said head; and means carried by the punches for returning to the web the disks cut out of the same by the punches, the strippers of one set being mounted to engage the disks of one set of the same before the strippers of the other set come into operation; with means for directing certain 115 of the lines of caps into separate receptacles.

7. The combination in a cap punching 120 machine of means for forming and delivering caps in a plurality of lines; a conveyer placed to receive such lines of caps from said means; and a plurality of independent receptacles placed to receive the caps of the 125 different lines.

8. The combination in a cap punching machine of means for forming and delivering

caps in a plurality of lines; a conveyer placed to receive the lines of caps from said means; a plurality of independent receptacles for the caps; with deflectors for causing the caps of a plurality of lines to be delivered into each receptacle.

5 In testimony whereof, I have signed my

name to this specification, in the presence of two subscribing witnesses.
